OPPOSED TABLE

Edward C. Krueger, Otsego, Mich., assignor to Hammond Machinery Builders, Inc., Kalamazoo, Mich., a corporation of Michigan

Filed July 21, 1958, Ser. No. 749,934

2 Claims. (Cl. 51—240)

This invention relates to a work feeding means and particularly to a type thereof adapted for applying a pressure of low but accurately controllable magnitude to a workpiece as same is fed to a work accomplishing device, such as a grinding wheel and particularly to an electrolytic type of grinding wheel.

While the substance of the present invention is applicable in a variety of work feeding devices, it has been developed for particular application to the feeding of the tool bits and similar small workpieces to a grinding wheel. Therefore, the description will proceed with reference to this use, but such reference will be understood as solely for convenience in description and will not be limiting.

Frequently, the feeding of tool bits and similar small workpieces to a grinding wheel is handled manually, but in feeding large numbers of small workpieces on a production basis to grinding wheels, it often is desirable to provide suitable power feed apparatus utilizing a pressure fluid. In view of the greater initial cost, maintenance problems and other difficulties often incident to the use of hydraulic feeding devices and since compressed air is normally available in most places where grinding devices are used, it is especially desirable that such feeding apparatus be air driven. This, however, introduces other problems which are discussed below.

With more and further reference to an electrolytic grinding operation, attention is called to the following circumstances and considerations which exist in the practice of electrolytic grinding and all of which are well-known to persons acquainted with apparatus of that type:

(1) In the sizes and types of workpieces feeding equipment usually employed and utilizing a power cylinder driven by an elastic fluid such as compressed air, there is required a line pressure of approximately 25 or more p.s.i. merely to overcome the exhaust back pressure and the friction normally existing between the piston and the cylinder walls. If an appreciably lesser pressure is supplied, the plunger of the power cylinder will often stop in the mid-stroke in a well-known but nevertheless entirely unpredictable manner. This is particularly true where a restricted exhaust is used to slow the final approach to the end of the stroke.

(2) Some additional force must be applied to the table in order to overcome the inertia which develops when the table accelerates.

(3) Therefore, it is necessary with an elastic fluid to supply same under a rather substantial pressure to the power cylinder in order to secure its reliable operation and to positively prevent such stopping or "hanging-up."

(4) Normally, in operating an electrolytic grinding machine, the operator watches an ammeter which indicates the amount of current flowing through the working surface of the workpiece, which current under a given set of conditions is a direct function of the pressure existing between the workpiece and the abrasive surface. This pressure is held by the operator at the proper values indicated by the ammeter and is of sufficiently critical nature that it must be closely controlled for proper results.

(5) The workpiece is, in a typical usage, urged against the grinding wheel under a pressure of approximately 100 pounds per square inch of working surface of the workpiece. However, having in mind that such working surface is sometimes of the order of only one or two one-hundredths of a square inch in area, it will be recognized

2

that in such cases only one or two pounds of force need be applied to the workpiece to urge it against the grinding wheel with the proper amount of pressure.

Thus, if the pressure is supplied to the power cylinder at such a value that it will apply only one or two pounds of pressure onto the workpiece, it follows that only one or two pounds of force is desired from the cylinder over that required to move the cylinder against friction and other resistances within the apparatus such as table inertia. Thus, to keep the output of the cylinder at this low level, the pressure applied to the cylinder will be insufficient to move the plunger freely and reliably and it will be too likely to "hang-up" unpredictably from time to time during otherwise normal operation of the apparatus.

Accordingly, a major object of the invention is to provide reliably operable apparatus utilizing an elastic pressure fluid for applying an accurate, rapidly selectable, and closely controllable force of relatively low magnitude onto a work feeding device, such as the work carrying table of an electrolytic type of grinder.

A further object of the invention is to provide apparatus in which sufficient pressure can be applied to the power cylinder that it will operate freely and reliably through repeated cycles of operations and with no danger of "hanging-up" in mid-stroke, but which can nevertheless apply to a workpiece a total force of only one or two pounds urging it against a metal cutting device, such as a grinding wheel.

A further object of the invention is to provide a device, as aforesaid, wherein the adjustment of said output force through a wide range of magnitudes can be easily and rapidly effected by use of simple mechanism.

A further object of the invention is to provide a device, as aforesaid, wherein the output force thereof is subject to accurate control through such wide range of magnitudes and, further, wherein when said output force is once selected it can either be maintained precisely within narrow limits of variation or accurately and rapidly further changed as desired.

A further object of the invention is to provide a device, as aforesaid, which is sufficiently simple in construction as to be capable of manufacture, installation, use and maintenance at very low cost.

A further object of the invention is to provide an apparatus, as aforesaid, which can be applied to convenient work feeding devices of presently known types without material modification thereof.

Other objects and purposes of the invention will be apparent to persons acquainted with devices of the general type upon reading the following disclosure and upon inspection of the accompanying drawings, in which:

FIGURE 1 is a front view of a grinding machine embodying the invention.

FIGURE 2 is a sectional view taken on the line II—II of FIGURE 1.

General description

In general, the objects and purposes of the invention are carried out by providing a generally conventional pressure cylinder in operative association with a work feeding device, such as a table carrying device, in association with a metal cutting means, such as a grinding wheel. A supply of pressure fluid of a substantially constant pressure value is connected to said cylinder. Opposing the pressure cylinder is a suitable force producing device whose force output is independent of the frictional effects within the pressure cylinder but which may be accurately and rapidly varied. A coil spring is a typical device meeting these requirements and is arranged so that the force imposed by the spring will oppose movement of said work holding device in response to pressure supplied thereto from said pressure cylinder. Thus, the net output force

applied to feed the work is the difference between the pressure exerted by said pressure cylinder and the opposing pressure exerted by said coil spring. By suitably adjusting said coil spring, the opposing force exerted thereby is accurately variable at will and within extremely close operating limits.

Detailed description

Referring now to the drawings, there is shown one form of apparatus by which the present invention may be carried out. This particular apparatus is, however, utilized merely for illustrative purposes and it will be recognized that the disclosure herein set forth is not intended to be limiting.

Referring to the drawings, there is shown a grinding wheel 1 associated with a table 2 and a hood structure 3, all of which are set forth in more detail in the application of March 29, 1956, Serial No. 574,728 and assigned to the same assignee as the present application. Said table is supported on the frame 4 of the machine for reciprocation therewith by any suitable means, such as the ball bearing structure generally indicated at 6.

Referring now to FIGURE 2, there is shown a base plate 7 to which the table 2 is mounted and which supports and moves the table toward and away from the grinding wheel 1 in a manner set forth in detail in the above-identified application, Serial No. 574,728. A fluid pressure cylinder 8 is mounted between the base plate 7 and the frame 4 in any convenient manner. In the particular embodiment herein shown, the casing of said cylinder is mounted through universal joint linkages 9 and 11, to the post 12, which is in turn mounted onto the frame structure 4. The plunger 13 associated with said cylinder is mounted through an adjustable rod 14 and a yoke 16 to the base plate 7. Suitable pressure fluid means, not shown, are provided for supplying pressure fluid at a constant pressure value to said cylinder 8 in the usual manner.

A plate 17 is affixed by a screw 18 to the forward side of the base plate 7 and extends downwardly therefrom. Said plate 17 contains bearing means 19 therein rotatably supporting the shaft 21 which carries a hand wheel 22 at its outer end and is suitably threaded at 23 inwardly from the plate 17. The leftward (as appearing in FIGURE 2) end 25 of the shaft 21 is of reduced size and slidably extends through a suitable bearing opening 24 in the structure of the frame 4. A reinforcing plate 26 may be applied to said frame structure at the point through which the shaft 21 extends, if desired. A nut 27 is threaded on the threaded portion 23 of shaft 21 and a spring 28 is disposed between said nut 27 and the plate 26.

A slide rod 29 is provided for prevention of rotation of the nut 27. Said rod is firmly received into a suitable opening 31 at the lower end of the plate 17, as by press fitting which may, if desired, be reinforced with a set screw or other suitable holding means, and said rod extends through a further opening 32 in the frame 4 of the machine. The plate 26 may extend downwardly sufficiently to be in register with the opening 32, and if so it is provided with a further opening in register with the opening 32 through which said slide rod 29 extends. A spring backing plate or collar 33 is provided at the end of said slide rod 29 and a spring 34 is located between said spring backing plate 33 and the adjacent structure of the frame 4.

Thus, the spring 28 will resiliently oppose movement of the base plate 7 leftwardly with respect to the frame 4, which direction corresponds to movement of the table 2 toward the grinding wheel 1, and the magnitude of said resistance is determined by the adjustment of the nut 27 axially along the shaft 21 in response to rotation of the hand wheel 22. The spring 34 on the slide rod 29 resiliently cushions the rightward motion of the base plate 7 with respect to the frame 4, which corresponds to motion of the table 2 away from the wheel 1.

Thus, when work is to be moved toward the wheel 1 on and by the table 2, and it is desired to have only a light pressure thereon between the work and the grinding wheel, the hand wheel 22 is adjusted so that the resilient force of the spring 28, when said spring is compressed to a point corresponding to the point at which work is in contact with the wheel 1, is sufficiently less than the force exerted by the cylinder structure 8, that the net force exerted by said cylinder structure onto the feeding table for urging said work against the wheel 1 will be of the magnitude desired. In this way, the pressure supplied to the cylinder may be of sufficiently high magnitude that there is no possibility of the cylinder's "hanging-up" at some unpredictable point and time in its operating cycle and yet the actual force applied to the workpiece will be of whatever relatively low magnitude is desired. Further, the feeding pressure applied to the work can be readily adjusted merely by adjusting the hand wheel 22 rather than engaging in the more complicated and often time-consuming adjustments of the pressure of the cylinder actuating fluid as is required by some present apparatus.

The spring 34 cushions the shock when the table is returned outwardly (rightwardly as appearing in FIGURE 2) which is also done under the force and by the agency of the pressure of cylinder 8.

Although particular preferred embodiments of the invention have been disclosed in detail above for illustrative purposes, it will be understood that variations or modifications of such disclosure, which lie within the scope of the appended claims are fully contemplated.

What is claimed is:

1. A work-feeding device particularly adapted for feeding small workpieces to a cutting tool, comprising: a frame; a work-supporting table mounted on said frame for reciprocating movement; a cylinder having a piston slidable therewithin in response to the supply of fluid pressure thereto and means connecting one of said piston and said cylinder to said frame and means connecting the other thereof to said table; a rotatable first shaft axially non-movably secured at one end to said table and means supporting the other end of said shaft for sliding movement with respect to said frame, said shaft having a threaded portion; a nut threaded onto said threaded portion of said shaft; a further shaft secured at one end to said table, the other end of said further shaft being mounted for sliding movement with respect to said frame, said further shaft being engaged with said nut to prevent rotation thereof around the first mentioned shaft; a coil spring mounted on said further shaft and disposed between said other end thereof and said frame for cushioning return of said table away from said cutting tool; a manually operable handle connected to said first shaft for rotating same and thereby causing said nut to move axially therealong; and a second coil spring surrounding said first shaft and disposed between said frame and said nut and operative to oppose movement of said first shaft and thereby said table in one direction, the magnitude of the force exerted by said second spring being sufficiently less than the force applied to said piston and cylinder that a net force of selected magnitude is applied to said table in a direction to urge said table toward said cutting tool, said second coil spring constituting the sole means opposing movement of said table toward said cutting tool and thereby controlling the pressure with which the workpiece contacts the cutting tool.

2. A work-feeding device particularly adapted for feeding small workpieces to a cutting tool, comprising: a frame, a work-supporting table mounted on said frame for reciprocating movement; a cylinder having a piston slidable therewithin in response to the supply of fluid pressure thereto; means connecting one of said piston and said cylinder to said frame and means connecting the other thereof to said table; a rotatable shaft axially non-movably secured at one end to said table and means sup-

porting the other end of said shaft for sliding movement with respect to said frame, said shaft having a threaded portion; a nut threaded onto said threaded portion of said shaft; an elongated guide element parallel with said shaft, said element being secured at one end to said table, the other end of said element being mounted for movement with respect to said frame, said element being engaged with said nut to prevent rotation thereof around said shaft; a manually operable handle connected to said shaft for rotating same and thereby causing said nut to move axially therealong; and a coil spring surrounding said shaft and disposed between said frame and said nut and operative to oppose movement of said shaft and thereby said table in one direction, the magnitude of the force exerted by said spring being sufficiently less than the force applied to said piston and cylinder that a

net force of selected magnitude is applied to said table in a direction to urge said table toward said cutting tool, said coil spring constituting the sole means opposing movement of said table toward said cutting tool and thereby controlling the pressure with which the workpiece contacts the cutting tool.
